UNITED STATES PATENT OFFICE

107,540

DESIGN FOR A MILK PAIL

Thomas D. McHale, Los Angeles, Calif.

Application September 7, 1937, Serial No. 71,494

Term of patent 14 years

To all whom it may concern:

Be it known that I, Thomas D. McHale, a citizen of the United States, residing at Los Angeles, in the county of Los Angeles and State of California, have invented a new, original, and ornamental Design for a Milk Pail, of which the following is a specification, reference being had to the accompanying drawing, forming part thereof.

The figure is a perspective view of a milk pail, showing my new design.

I claim:

The ornamental design for a milk pail, as shown.

THOS. D. McHALE.
